UNITED STATES PATENT OFFICE.

GASTON HERVIEU AND CHARLES THUILLET, OF PARIS, FRANCE.

ACETYLENE-GAS GENERATOR.

No. 825,213.

Specification of Letters Patent.

Patented July 3, 1906.

Application filed September 7, 1905. Serial No. 277,342.

To all whom it may concern:

Be it known that we, GASTON HERVIEU, residing at 33 Rue Lamarck, and CHARLES THUILLET, residing at 5 Rue Villedo, Paris, France, citizens of the French Republic, have invented certain new and useful Improvements in and Relating to Acetylene-Gas Generators; and we do hereby declare the following to be a full, clear, and exact description of the invention, such as will enable others skilled in the art to which it appertains to make and use the same.

This invention has for its object improvements in apparatus relating to acetylene-gas generation, and is especially designed for the purpose of feeding automatically to an acetylene-gas generator cylindrical or spherical carbid-cartridges.

The drawings accompanying this specification show one way of carrying out this invention with regard to an acetylene-gas generator.

Figure 1 is an elevation of a gas-generator with gasometer complete. Fig. 2 is a vertical section of the generator. Fig. 3 is a vertical section of the apparatus for distributing the cartridges, which view is drawn to a larger scale than the other figures. Figs. 4 and 5 are horizontal sections on the lines A A and B B, Fig. 3. Fig. 6 is a diagram showing the various positions of the cartridges in the distributer. Fig. 7 is a vertical section of a cartridge-holder.

The same numerals of reference are employed to denote the same parts in all the views.

The apparatus shown on the drawings consists of a generator 1, the outlet-tube 2 of which extends to the bell 3 of the gasometer 4, the construction of which is of no importance. The generator may be varied, as the essential part of this invention consists of the arrangement of the cartridge-distributer placed at 5; but we prefer to arrange the gas-generator as follows: 1 is a tank which forms the generator. This tank has an inclined bottom and is divided into two parts by a partition 9, one of which parts is again subdivided into two parts 6 and 7 and provided with a top 8. At the bottom of this chamber a basket 10 may be placed, passing under the partition 9. This basket is furnished with a handle 11 to facilitate manipulation. The basket is for the purpose of receiving the

cartridges and for removing them when exhausted from the generator. Between the compartments 6 and 7 are fixed one or more transverse partitions 12, thus dividing the whole chamber into two compartments, the first of which serves as a chamber for the gas, with which the exit-pipe 2 communicates, and the second compartment receives the cartridges as they are distributed and also conducts such cartridges to the basket 10. These cartridges are conducted under the compartment 6 by means of an inclined plane 14, which also prevents the gas from the cartridges escaping into the compartment 7 or into the distributer 5 or cartridge-holder 15 placed above.

The distributer 5 consists, essentially, of curved slides 16, 17, and 18 (forming a sinuous path to guide the cartridges) and movable parts for retaining the cartridges and liberating them one at a time. These movable parts consist of rollers 19, mounted on an axle 20, fixed to two sectors 21, the pivots of which, 22, are carried at the side of the distributer 5. The sectors 21 are also connected rigidly by a cross-bar 23, to which is articulated an arm 24, which passes through an opening in the distributer and serves to raise or lower the rollers 19. To effect this, the arm 24 is connected by a flexible attachment 25 to a sliding piece 26, which is arranged so as to be actuated by a finger 27, fixed rigidly to the bell 3. Each time the bell descends sufficiently the arm 24 is raised and the rollers 19 are raised, as indicated at I, Fig. 6. The cartridge 28, which has been retained in the slides 18 by the rollers 19, is now liberated and falls into the generator, while the next cartridge 29 rests on the slide 16 and on the rollers 19.

As the bell 3 rises by the action of the gas generated by the cartridge 28 the rollers 19 descend, and the cartridge 29, resting on the rollers 19, can roll round the point of junction of the slides 16 and 18 and enter the slide 18 when the rollers 19 have arrived at the position III. The cartridge 29 then takes the position of the preceding cartridge, (indicated at 28,) so that at the next descent of the bell the rollers 19 can be raised afresh and pass above the cartridge 29, letting it fall into the generator at the moment when the rollers arrive in contact with the next cartridge 30, which then takes the position

marked at 29. The diagram Fig. 6 indicates the geometrical lines of the slides 16, 17, and 18, and it only remains to observe that those parts of the slides on which the cartridges do not rest during their travel can be arranged otherwise or dispensed with entirely without inconvenience. This very simple method of distribution has the advantage of working without knocks or shocks, the column of cartridges rests constantly on rollers 19, and the movement is progressive, as each cartridge is only able to fall at the moment when the roller 19 is in a position under the next cartridge to prevent its falling. Further, only a small amount of force is required to move the distributor, because at no time have the rollers 19 to lift the bulk of the cartridges.

If necessary, the rollers 19 can be replaced by a long roller of any suitable form in longitudinal section.

31 shows a flap arranged under the distributor to prevent the steam or moisture from the generator acting on the new cartridges. This flap is opened by the weight of each cartridge, as at Fig. 3, the flap being returned to its normal position by any suitable means, such as a spring. (Not shown.)

The cartridge-holder or magazine consists of a box 15, closed at the top and open at the bottom, such box being fixed by means of a catch to the distributor. In order to hold the cartridges in the holder, a roller 32 is mounted on arms 33, which extend outside to a spur 34, carrying a handle 35. When the handle is raised, the roller 32 is brought to the opening in the box, thus preventing the cartridges from falling out. On arms 33 are formed hooks 36 to engage with a lug 37 on the distributor, so as to fix the cartridge-holder on this latter. On lowering the handle 35 the hooks 36 engage at the same time as the cartridges are being liberated. Lugs 38, formed on the distributor, keep the cartridge-holder in its proper position.

The cartridge-holder can be of any suitable size, so that the cartridges may be in a straight line or in a zigzag line, as at Fig. 7.

Carbid cartridges are represented as being made of agglomerated carbid or inclosed in tubes of cardboard, paper, or other suitable material. The space between the partitions 12 forms a safety-chamber 39 to catch and conduct the gas which might escape from the compartment 6 in case the apparatus should run short of water or through extra pressure on the bell.

Without departing from the present invention the method of transmitting the motion of the bell of the mechanism can be varied.

What we claim as our invention, and desire to secure by Letters Patent of the United States of America, is—

1. In an acetylene-gas generator, the com-

bination of the generator-casing, a distributor mounted thereon and provided with lugs, and a removable cartridge-holder adapted to fit upon the top of said distributor and provided with mechanism at the bottom for holding the cartridge in place in the holder and with gripping means connected to said mechanism so that they work in unison, said means being adapted to lock said holder to said distributor, substantially as described. 65

2. In an acetylene-gas generator, the combination of the generator-casing having a distributor mounted thereon and having its interior arranged at different inclines, a vibrating roller mounted on a sector in said interior, a gas-bell, and connections between said sector and said gas-bell, whereby the fall of said bell lifts said rollers and releases a cartridge, substantially as described. 70

3. In an acetylene-gas generator, the combination of a generator-casing divided into chambers, a distributor provided with a pivoted bottom mounted on said casing above one of said chambers, said distributor being provided with inclines on its interior for guiding the cartridges, and also provided with a pivoted bottom, a sector pivotally mounted in the lower part of said distributor and carrying rollers normally adapted to support the cartridges, a gas-bell, and connections whereby the fall of the gas-bell lifts said sector and releases a cartridge, substantially as described. 85

4. In an acetylene-gas generator, the combination of a generator-casing, a distributor mounted thereover and provided with inclines on its interior, with a pivoted bottom and with lugs on its sides and projections on its top, a cartridge-holder adapted to fit in between said projections, said cartridge-holder having a closed top and provided with movable means at its bottom for holding the cartridges therein, and gripping means carried by said holding means and adapted to engage the lugs on said distributor, substantially as described. 90

5. In an acetylene-gas generator, the combination of a generator-casing, a distributor thereon provided with lugs on its sides, a cartridge-holder provided with a closed top and with a roller pivoted in its bottom, a handle 100 for operating said roller, and gripping means operated by said handle for engaging the lugs on the distributor, whereby the movement of the handle to lock the cartridge-holder upon the distributor, releases the cartridges, substantially as described. 105

6. In an acetylene-gas generator, the combination of a generator-casing divided into chambers, a distributor mounted above one of said chambers and having its interior provided with various inclined portions and with a pivoted bottom, a sector pivotally mounted near the bottom of said distributor and 115

provided with rollers for regulating the feed of the cartridges, a rod attached to said sector and passing through the side of the distributor, a pivoted connection carrying a stop, said connection being attached to said rod, and a gas-bell provided with a projection adapted to engage said stop, substantially as described.

In testimony whereof we affix our signatures in presence of two witnesses. 10
